United States Patent Office

Des. 220,981
Patented June 22, 1971

220,981

TWO-STAGE AEROSPACE VEHICLE

James E. Webb, Administrator of the National Aeronautics and Space Administration, with respect to an invention of Harold S. Becker, Palos Verdes Estates, Selwyn Enzer, Orange, William H. Hand, Redondo Beach, Peter Rosati, Garden Grove, and Norman C. Surtees, San Pedro, Calif.

Filed Feb. 5, 1965, Ser. No. 83,872

Term of patent 14 years

Int. Cl. D12—07

U.S. Cl. D71—1

FIG. 1

FIG. 1 is a perspective view of the two-stage aerospace vehicle or similar article;

FIG. 2 is a plan view of the two-stage aerospace vehicle or similar article;

FIG. 3 is a side elevational view of the two-stage aerospace vehicle or similar article; and

FIG. 4 is a rear elevational view of the two-stage aerospace vehicle or similar article.

What is claimed is:

The original design for a two-stage aerospace vehicle, substantially as shown.
